FRIEDRICH STOCK, OF ESSEN-ON-THE-RUHR, GERMANY, ASSIGNOR TO FRIED. KRUPP AKTIENGESELLSCHAFT, OF ESSEN-ON-THE-RUHR, GERMANY.

WHEELED GUN CARRIAGE WITH SPREAD-OUT TRAIL.

1,403,818.

Specification of Letters Patent. Patented Jan. 17, 1922.

Application filed February 12, 1915. Serial No. 7,773.

To all whom it may concern:

Be it known that I, FRIEDRICH STOCK, residing at Essen-on-the-Ruhr, Germany, a citizen of the German Empire, have invented a certain new and useful Improvement in Wheeled Gun Carriages with Spread-Out Trail, of which the following is a specification.

The present invention relates to wheeled gun carriages with spread out trail and resides in a novel solution of the problem of making possible a stable positioning of the gun carriage on uneven ground.

In the accompanying drawing

15 Fig. 1 shows one embodiment of the invention as a side view, partly in section, of the parts concerned of a gun carriage;

Fig. 2 the corresponding top plan view, partly in section along line 2—2 of Fig. 1, 20 but without gun-barrel, cradle and top carriage;

Fig. 3 a similar view to Fig. 1 of a second embodiment of the invention and

25 Fig. 4 the corresponding top plan view, partly in section along line 4—4 of Fig. 3.

The gun carriage illustrated in Figs. 1 and 2 will first be described. The axle tree A of the gun carriage is provided with two cranked portions offset 180° against each other. On the crank journals a^1 and a^2 , formed in this manner, and the geometrical axes of which run parallel to the axis of revolution of the wheels J, are revolubly mounted the two rearwardly diverging trail sides 30 B and B^1 , through the intermediary of two-part slides C, which embrace the journals a^1 , a^2 and are slidable in bearings b^2 of the trail sides B B^1 . Between the trail sides B B^1 are inserted, in the usual manner, links, 35 not shown, for the purpose of coupling together the trail ends during transportation of the gun carriage. Between the inner crank arms a^3 of the journals a^1 , a^2 , see Fig. 2, is revolubly mounted around the axle tree 40 A, a member D. This member is provided with a socket d^1 , Fig. 2, for the vertical pivot e^1 , Fig. 1, of the top carriage E, in which the cradle F, carrying the gun barrel, is mounted by means of horizontal trunnions 45 f^1 . An elevating gear G G^1 , Fig. 1, having a toothed arc, is inserted between the top carriage E and the cradle F, whilst the top carriage E may be trained relative to the member D by means of a training gear, not shown. The trail sides B B^1 and the mem-

ber D are provided with extensions b^3 and d^2 , respectively, which are hinged together by means of a pin H.

In consequence of the described arrangement, the following movements will occur, 60 on unlimbering the gun carriage on ground, where the four sustaining points for the gun carriage, namely, the contact places of the wheels J, and the two trail sides B B^1 , are not situated in one and the same plane. As 65 soon as one of the trail sides, B for instance, has reached the ground, the other trail side B^1 actuated by the preponderence of the gun carriage lowers itself with regard to the trail side B, so that the free end of the extension 70 b^3 of the trail side B^1 moves upwards. Simultaneously the axle tree A turns slightly in the wheels J in such a direction, that the crank journal a^2 swings downwards and the crank journal a^1 upwards. The trail side B 75 with its extension b^3 partakes in the upward movement of the crank journal a^1 , without losing its hold on the ground. The slides C simultaneously suffer a slight displacement in their guides b^2 . During this movement of 80 the trail sides B B^1 and the axle tree A, the member D does, moreover, by means of the pin H, perform a slight oscillation around the axle tree in the direction of the arrow x, Fig. 1.

With regard to the embodiment shown in Figs. 3 and 4, the axle tree A, upon which the trail sides B B^1 and the member D are revolubly mounted, is in this case straight, not cranked; but the extensions b^3 of the 85 trail sides are on the other hand connected with the extension d^1 of the member D, by means of a crank shaft K k^1 k^2 , the crank journals, k^1 k^2 of which are angularly displaced 180° relative to each other. This 90 crank shaft rests revolubly in a bearing of the extension d^1 which is closed by a cover d^2 . The journals k^1 and k^2 , which are parallel to the axis of revolution of the wheels J, are mounted in two-part slides M, which 100 are displaceable in guides b^4 of the trail side extensions b^3 .

Also with this arrangement the rear ends of the two trail sides B B^1 may adjust themselves relative to each other at different 105 heights, within certain wide limits. With regard to the operation of this arrangement, it should only be mentioned, that through opposite movement of the two trail sides, a turning of the crank shaft in the bearing 100

d^1 d^2 occurs, as well as an oscillation of the member D around the axle tree A. The slides M simultaneously execute a displacement in the guides b^4 .

5 I claim:—

1. A wheeled gun carriage having an axle tree and a rearwardly spread-out trail, comprising two separate trail-sides, and a crank-shaft device having journals connecting said 10 trail-sides with each other and with said axle tree; said journals running parallel to the axis of revolution of the carriage wheels.

2. A wheeled gun carriage having a gun supporting member and two separate trail 15 sides, a straight common journal for said member and said trail sides and a crank shaft having journals connecting said trail sides with said member, the axes of said crank shaft journals and of said straight 20 journal all being parallel with the axis of rotation of the carriage wheels.

3. A wheeled gun carriage having a gun supporting member and two separate trail sides, a straight common journal for said 25 member and said trail sides and a crank shaft having journals connecting said trail sides with said member, the axes of said crank shaft journals and of said straight journal all being parallel with the axis of 30 rotation of the carriage wheels, and the axis of oscillation of said member coinciding with the axis of revolution of said wheels.

4. A wheeled gun carriage having a gun supporting member and two separate trail sides, a straight common journal for said 35 member and said trail sides and a crank shaft having journals connecting said trail sides with said member, the axes of said crank shaft journals and of said straight journal all being parallel with the axis of 40 rotation of the carriage wheels, sliding bearings for said crank shaft journals and guide-ways in the trail sides for said sliding bearings.

5. A wheeled gun carriage having a gun 45 supporting member and two separate trail sides, a straight common journal for said member and said trail sides and a crank shaft having journals connecting said trail sides with said member, the axes of said 50 crank shaft journals and of said straight journal all being parallel with the axis of rotation of the carriage wheels, sliding bearings for said crank shaft journals and guide-ways in the trail sides for said sliding bearings, the journal around which said member 55 oscillates being in alignment with, and integral with the axle tree.

The foregoing specification signed at Bar-
men, Germany, this 31st day of Dec., 1914. 60

FRIEDRICH STOCK. [L. S.]
In presence of—
HELEN NUFER,
ALBERT NUFER.
